UNITED STATES PATENT OFFICE.

RIVEN TOVE, OF SOUTH NORWALK, CONNECTICUT.

CORSET STAY.

Application filed May 31, 1922. Serial No. 564,747.

To all whom it may concern:

Be it known that I, RIVEN TOVE, a citizen of the United States, residing at South Norwalk, county of Fairfield, State of Connecticut, have invented an Improvement in Corset Stays, of which the following is a specification.

This invention relates to corsets and particularly to the stays or stiffening elements 10 therefor.

It is an object of the invention to provide a stay or stiffening element which will have a tip or end which is flexible and which will yield under pressure both longitudinally of 15 the stay and transversely thereof as the wearer bends but will return to the original position immediately the wearer straightens.

It is also an object of the invention to provide a stiffening element in which the probability of injuring the wearer is very remote and also one in which the ends will not tend to force through the cloth of the corset tearing the same and also injuring the wearer.

It is a further object of the invention to provide a stiffening element which is not liable to breakage and so will reduce liability of injury to the wearer.

It is a still further object of the invention 30 to provide a spring tip for corset stays and clasp steels that will adjust itself to the figure of the wearer giving the proper and desired effect without danger of injury or annoyance and which at the same time holds 35 the corset in proper position without wrinkling the material.

With these and other objects in view I have devised the construction illustrated in the accompanying drawing, in which

40 Fig. 1 is a plan view of a section of a corset showing my stiffening element applied thereto.

Fig. 2 is a side view of the stiffening element removed.

45 Fig. 3 is an edge view thereof.

Fig. 4 is an edge view of one end thereof showing the tip bent to one side, and

Fig. 5 is a side view of the modified construction of the stiffening element.

50 The body of the corset, represented by the numeral 10, may be of any desired material in which is sewed in the usual manner the stiffening elements, such as stays 11 of which I have illustrated two, and the clasp steel

55 12 at the free edge of which I have shown one only. As my improved tip may be ap-

plied equally well to the stays or clasp steels, I have for brevity employed the term stay in the generic sense as including the stay proper or the clasp steel. In the form shown 60 in Figs. 1 to 4, the body of the stay is made of the usual flat thin strip of steel 13 which in the ordinary construction has its free ends covered with a metal cap of some kind. These stays will yield laterally a certain amount but the greater part of the yielding 65 will be at the center with very little at the ends so that they are very uncomfortable to the wearer of the corset when she bends over.

Referring to my invention I apply a flexible resilient tip for these stays and prefer to put a tip of this character on each end of the stay. This tip is a flattened coil of wire, 75 preferably a flattened helical spring, a few of the coils of which are wrapped around the end of the flat body, as shown at 14, and the coils 15 beyond the ends of the body are spaced from each other, as shown, to allow the tip to yield not only laterally but also 80 longitudinally of the stay. This tip may be of uniform width but I prefer to make the two or three coils at the end thereof of somewhat smaller diameter than the remaining coils, as shown at 15', so as to give a 85 slightly rounded effect to the free end of the tip. The tightly wrapped or securing coils 14 may be wound around the end of the body portion without reducing the width thereof but I prefer to reduce the ends of the body, 90 as shown at 16, so that when the resilient tip is applied the stay will be of substantially uniform width throughout. Also the shoulders 17 will prevent the tip from pushing down too far onto the body portion. 95 When the stay is sewed into the corset, as it is entirely enclosed, the stitching will prevent the tip loosening and moving off the body portion.

In the modified construction shown in 100 Fig. 5, I form the entire stay of a single piece of wire in the form of a flattened helical spring or coil, the body portion 18 having the adjacent coils close together or 105 in contact while the desired number of coils at the end of the stay are separated, as shown at 19, to provide the resilient tip corresponding to that applied to the stay as shown in Figs. 1 to 4.

When the corset including my improved 110 stays is worn the flat body portion of the stays will hold the corset to the figure of

the wearer without wrinkling the material and thus spoiling the effect desired, as when the wearer bends or sits down instead of all of this bend being compensated for in the 5 body of the stays this body portion keeps its proper position and the ends of the stay yield both longitudinally and laterally of the stay as required, the lower ends being at substantially the so-called hinge. As 10 these tips are of very flexible resilient material and the ends of the stay are blunt, they will not press into the body of the wearer, but they will form sufficient support and one which is sufficiently yielding to not 15 only not injure the wearer but will cause no discomfort or annoyance. As these tips are made of very flexible resilient material there is very little probability of their breaking and causing injury to the wearer. 20 With the ordinary flat steels when they break, which is more or less common, the sharp rough broken ends tear through the cloth of the corset and often cause serious injury to the wearer. This danger is practically eliminated in my form of stay. It 25 will be apparent from an inspection of the drawing that the free ends of the tips are blunt, and, therefore, will not be liable to push their way through the walls of the enclosing material. Immediately the wearer returns to a straightened position after bending, the flexible resilient tip also returns to a straightened position at the same 30 time acting as a support for the busts. 35 When the wearer is bending over it also takes the weight although at the same time yielding downwardly so as to give a relief not obtainable with the ordinary straight stay. It is very sensitive and so gives perfect freedom.

Having thus described the nature of my invention, what I claim is:

1. A corset stay comprising a body portion of resilient material yieldable laterally of the stay but being substantially non-yieldable longitudinally thereof, and a cushion spring tip at the end of said stay yieldable both laterally and longitudinally of the stay.

2. A corset stay comprising a body portion of resilient material yieldable laterally of the stay but being substantially non-yieldable longitudinally thereof, and a resilient tip for said stay composed of a flat coil of wire having the adjacent turns 55 spaced from each other.

3. A corset stay comprising a flat, flexible, resilient body portion adapted to yield laterally but being substantially nonyieldable longitudinally of the stay, and a resilient tip for said body portion comprising a flattened helical spring with the adjacent convolutions spaced from each other and the convolutions at the free end thereof becoming gradually smaller to give a tapered effect to the free end of the tip.

4. A corset stay comprising a flat, flexible, resilient body portion narrowed adjacent its end and a resilient tip for said body portion comprising a flat helical coil of 70 wire with a portion of its convolutions embracing said narrowed portion of the body and the convolutions beyond this end spaced from each other.

5. A corset stay comprising a flat flexible 75 resilient body portion substantially nonyieldable longitudinally thereof, and a tip for said body portion comprising a flat, flexible, resilient coil of wire of less stiffness than the body portion and having the adjacent convolutions thereof spaced from each other.

6. A corset stay comprising a flat, flexible, resilient body portion with the edges removed adjacent its end to provide a portion narrower than the remainder of the body and to provide shoulders on opposite sides of the body at the inner end of this narrowed portion, and a separate resilient tip for said body portion comprising a flat 90 helical coil of wire with a portion of its convolutions embracing said narrowed portion of the body with the shoulders limiting its inward movement and the convolutions beyond this end being spaced from 95 each other.

In testimony whereof I affix my signature.
RIVEN TOVE.
